UNITED STATES PATENT OFFICE.

BENJAMIN M. DES JARDINS, OF WEST HARTFORD, CONNECTICUT.

MECHANISM FOR USE IN GRINDING TWIST-DRILL POINTS AND THE LIKE.

Application filed March 25, 1921. Serial No. 455,486.

To all whom it may concern:

Be it known that I, BENJAMIN M. DES JARDINS, a citizen of the United States, and a resident of West Hartford, in the county 5 of Hartford, State of Connecticut, have invented certain new and useful Improvements in Mechanism for Use in Grinding Twist-Drill Points and the like, of which the following is a specification.

10 The present invention relates generally to mechanism for use in grinding the points of twist drills and the like, and particularly to means for properly positioning and supporting the drills relative to the grinding 15 wheel.

It is the aim of the present invention to provide mechanism of this sort having features of novelty and advantage and which is especially characterized by its decided 20 simplicity in construction, thus providing for economy in manufacture and consequently its sale at a relatively low cost; and its efficiency and accuracy in operation in that by its use the point of the drill may be 25 readily ground with precision to the desired shape and size.

The embodiment of the invention here selected for purpose of illustration will be described with reference to its use for grinding 30 the point of a twist drill. It is to be understood, however, that the present disclosure is by way of exemplification only as the invention is susceptible of various modifications and embodiments. Furthermore, 35 in describing the present embodiment of the invention, conventional terms will be employed, but it is to be understood that these terms are used solely for purpose of description and they are not to be taken as 40 having any limiting effect.

In the accompanying drawings:—

Fig. 1 is a side elevational view of a device constructed in accordance with the present invention.

45 Fig. 2 is a top plan view thereof.

Fig. 3 is a sectional view taken substantially on line 3—3 of Fig. 2 and looking in the direction of the arrow.

50 Fig. 4 is a side view of a structure particularly adapted for use in positioning small drills in their holders.

Fig. 5 is a plan view thereof looking in the direction of the arrow 5 of Fig. 4, with the parts seen through the magnifying glass 55 enlarged.

Fig. 6 is a sectional view taken on line 6—6 of Fig. 4 and looking in the direction of the arrow.

Referring now to Figs. 1 to 3 inclusive, it will be seen that in its present embodiment, the device has a base plate 10 fixed on a suitable pedestal A at an angle to the face of the grinding wheel W corresponding to the angle between the cutting edges and the axis of a drill, which angle is usually about 59°. Adjustably mounted on this base plate 60 is a supporting plate 12, the side edges of the plate 12 being bent to form grooves 13 which slidably receive the edges of the plate 10. The plate 12 may be adjusted by means 65 of the micrometer screw 14 or otherwise. Slidably mounted, in a manner hereinafter described, upon the supporting plate 12 is a plate 17 which, for convenience, is herein referred to as a carrier for the drill holders 70 which may be of any suitable type. The drill holder 18 shown in Figs. 1 to 3 may be used for larger sizes of drills, while the holder 18a of Figs. 4 to 6 is particularly adapted for smaller sizes. The drill holder 75 18 has, as is usual, a V groove which receives the drill; a straight edge 19 with which the cutting edges of the drill are to be aligned; and a block 20 adapted to be adjusted by the screw 20a which is threaded in a second 80 adjustable block 20b secured in position by a screw 20c. By preference, the drill holders 85 are detachable from the carrier to permit holders adapted for different kinds of drills to be interchangeably mounted upon the carrier, and to this end the several holders 90 may have correspondingly spaced recesses 22 which receive projections 23 on the carrier, these projections in the present instance being in the form of dowel pins. 95

In order to grind the portions of the drill point back of the cutting edges and thus obtain lip clearance, it is necessary to swing the drill about a center adjacent the forward end thereof. For this purpose, interengaging 100 means are provided between the supporting plate 12 and the carrier 17 for guiding the latter in the proper path. This means, in the present illustrative disclosure, comprises slots 25 having arcuate edges 105 which are curved about a center lying in a line passing at right angles through the axis of the drill and adjacent the forward end thereof, and guiding studs or pins 26 carried by the supporting plate and engaging 110

in the slots. The center about which the carrier 17 turns is indicated at X, Fig. 2, and this center lies substantially in the line $a-b$ of Fig. 1. This arrangement provides for a very simple, compact and effective structure.

To set up the device, when the drill holder 18 is employed, the drill to be ground is positioned within the holder 18 with one of its cutting edges in parallelism with the straight edge 19 and then the block 20^b is adjusted until the block 20 contacts with the lower end of the drill. Any fine adjustment of the drill longitudinally of the holder 18 may be had by turning the screw 20^a. Then the supporting plate 12 may be longitudinally adjusted to its initial position by turning the screw 14 to move the point of the drill into correct relation with the line $a-b$ and proper engagement with the grinding wheel. During the grinding operation, the carrier is swung back and forth (being guided in its movement by the pins 26) to obtain the desired clearance or relief. After one side of the drill point is ground, the drill is rotated 180° within the holder and then the other side is ground.

In grinding a drill point, the cutting edge must be in parallelism with the grinding face of the wheel and to obtain maximum efficiency, it is necessary that the two cutting edges be of the same length and of the correct and same inclination to the axis of the drill. In grinding a small drill it is extremely difficult to meet these requirements where the drill is held in a holder such as is shown in Figs. 1 to 3 because of the inability to accurately align the cutting edges of the drill with the straight edge 19. For this reason, I have provided an improved holder for small drills and means for positioning the drills with accuracy in this holder. This improved holder, shown in Figs. 4 to 6 and designated by the character 18^a, comprises a rectangular block in which is positioned a pair of jaws 30 between which passes the stem 31 of a chuck 32 adapted to receive small drills. The jaws are clamped against the stem by means of a screw 33. On each of two opposite faces of the block are recesses 22 spaced apart correspondingly to the dowel pins 23 on the holder 17 so as to receive the same. The recesses in the opposite faces of the block are similarly positioned with respect to the axis of the stem 31.

The device for use in adjusting a small drill in the holder 18^a, preparatory to positioning this holder on the carrier 17, consists of a main plate 37 having at one end a frame 38 one end member of which has an opening 39 provided with a straight edge 40 which is at an angle of about 59° to the plate 37 and lies in a plane which is perpendicular to that plate. This frame also carries a magnifying glass 41 adapted to

be focused on the straight edge 40. Slidably mounted on the main plate 37 is a slide 42 provided with a pair of dowel pins 43 spaced correspondingly to the recesses 22 of the holder 18^a so as to receive the same. The slide 42 is adjusted by means of a micrometer screw 44 which is preferably similar to the screw 14. In one manner of speaking, the main plate and slide may be collectively referred to as a support for the frame 38 75 and the drill holder.

It will be apparent that should small drills be positioned in the holder 18, they will lie low in the V of this holder, and the line $a-b$ where it intersects the axis of the drill will necessarily be close to the point of the drill as it is ground by the wheel. As the drills grow larger, the points of intersection on the line $a-b$ and the axis of the drills recedes from the wheel, consequently increasing the cone of the ground portion of the drill. Now when the holder 18^a is employed, the center of the drill carried thereby will always be at the same height relative to the carrier 17. It is, therefore, necessary that the center about which this carrier turns be adjusted relatively to the grinding wheel in accordance with the size of the drill to be ground. That is, the operating center must be moved farther away from the grinder for a larger size drill than a smaller one. To obtain this adjustment, the micrometer screw 14 is turned until the readings thereon indicate that the supporting plate 12, together with the guide pins 26 carried thereby, have been moved to such a position that the carrier may be turned about a center having a predetermined relation to the grinding wheel to give to the drill the proper size and shape. 105

To properly position the drill in the holder 18^a so that when this holder is positioned on the pre-adjusted carrier 17 the point of the drill will be properly presented to the grinding wheel, the plate 42 of the device shown in Figs. 4 to 6 is adjusted by turning the micrometer screw 44 until the reading of this screw corresponds to that of the screw 14. The small drill is placed in the chuck 32 and the holder is positioned on the slide 42 with one set of recesses 22 receiving the dowel pins 43. Then the chuck 32 is turned and adjusted endwise until one of the cutting edges of the drill point, as viewed through the magnifying glass, is in alignment with and parallel to the straight edge 40. The screw 33 is then tightened to hold the chuck against rotary and longitudinal movement within the holder block 18^a. After thus positioning the drill in the chuck 32, the holder is positioned on the carrier 17 with one set of recesses 22 receiving the dowel pins 23. Since the drill has been adjusted in the holder 18^a in accordance with the predetermined adjustment of the supporting plate 130.

12, it follows the drill point will be in proper engagement with the grinding wheel and will be turned about the correct predetermined center X. During the grinding operation, the carrier is swung about the predetermined center, being guided in the proper path by the studs 26. After one edge of the drill point is ground, the holder is turned over with the other set of recesses 10 receiving the dowel pins 23 and then grinding of the other edge of the drill may be proceeded with with the assurance that this edge will be ground exactly to the same shape, size and angle as the first edge.

15 It is, of course, evident that the construction and arrangement of the devices here described are susceptible of various changes and reversal of parts; for instance, the drill may be stationarily mounted and the grinding member or wheel may be supported on a carrier which is guided in the proper path; also, the carrier 17 and the drill holder may be secured together and be considered as a drill holding unit.

25 I claim as my invention:—

1. In combination, a grinding wheel, a carrier mounted entirely outside of the plane of said wheel and to one side face thereof and having adjustment to and from said 30 side face of said grinding wheel and also being mounted for adjustment for movement in a curved path about a center adjacent said side face, a drill holder on said carrier, and means for adjusting said carrier to and from said 35 face to change the center about which it turns relative to the grinding wheel.

2. In combination, a grinding wheel, a supporting member mounted for adjustment to and from said wheel and provided with a 40 pair of studs, a carrier provided with arcuate slots receiving said studs, said slots being curved about a center adjacent the contact point between the drill and a side face of said wheel, a drill holder on said carrier, 45 and a screw for adjusting said supporting member to vary the center about which said carrier turns, said member, carrier and holder being located at one side of one of the side faces of said wheel and entirely out 50 of the plane of the wheel.

3. In combination, a grinding wheel, a carrier mounted for turning movement, a drill holder having two opposite faces parallel with each other, means for positioning 55 said holder on said carrier with either of said faces resting thereon, and means for

adjusting said carrier to change the center about which it turns relative to said grinding wheel.

4. In combination, a grinding wheel, a 60 base plate, a sheet metal supporting plate having its side edges turned back upon themselves to form grooves receiving all side edges of said base plate whereby said supporting plate is adjustable to and from said wheel, a 65 sheet metal carrier slidably mounted on said supporting plate and having arcuate slots, a drill holder on said carrier, and studs on said supporting plate engaging in said slots for guiding said carrier. 70

5. In a device for use in grinding drill points, a carrier provided with spaced projections, and a drill holder having opposite faces parallel with each other and each having a set of recesses spaced correspondingly 75 to said projections to receive the same, said sets of recesses being correspondingly positioned relative to the axis of said holder.

6. In a device for use in grinding drill points, a carrier provided with spaced projections, and a drill holder comprising a 80 block having a pair of opposite parallel faces each provided with recesses adapted to receive said projections, the recesses in said opposite faces being correspondingly 85 positioned with respect to the axis of the holder, a drill chuck having a stem passing axially through said block, and jaws within said block for clamping said stem in position. 90

7. In combination, a grinding wheel, a carrier for turning movement, a drill holder thereon, means for adjusting said carrier to vary the center about which it turns relative to the grinding wheel, and means for adjusting a drill in said holder in accordance with the adjustment of said carrier. 95

8. In combination, a grinding wheel, a supporting member mounted for adjustment to and from said grinding wheel, a carrier, 100 a drill holder, means for positioning said holder on said carrier, interengaging means between said supporting member and carrier for guiding the latter in a circular path, means for adjusting said supporting member to change the center about which said carrier turns, and means for positioning a drill in said holder comprising a straight edge, a slide, means for adjusting said slide relative to said straight edge, and means for 105 positioning said holder on said slide. 110

BENJAMIN M. DES JARDINS.
